UNITED STATES PATENT OFFICE.

JOSEPH HERMAN, OF RENO, NEVADA.

CHURN.

1,145,483.

Specification of Letters Patent. Patented July 6, 1915.

Application filed October 26, 1914. Serial No. 868,708.

To all whom it may concern:

Be it known that I, JOSEPH HERMAN, a citizen of the United States, residing at Reno, in the county of Washoe and State of Nevada, have invented certain new and useful Improvements in Churns, of which the following is a specification, reference being had to the accompanying drawings.

This invention relates to new and useful improvements in churns, and relates particularly to that class of churns which are provided with oscillating dashers.

An object of this invention is the provision of a churn of this character in which the dasher rod is pivotally connected to the cover of the churn, whereby when the cover is removed from the churn the dasher is also removed therefrom.

A further object of this invention is the provision of a churn in which improved and simple means is provided for locking the cover on the churn body when the churn is in use, the locking means comprising only one latch member, so that the cover may be quickly removed from the churn body when it is desired to fill the body.

Still another object of this invention is the provision of an improved dasher in which a plurality of blades are provided, the dasher and blades being formed from one piece of material.

With these and other objects in view, my invention consists in the novel construction, combination, and arrangement of parts, to be hereinafter more fully described, claimed, and illustrated in the accompanying drawing, in which—

Figure 1 is a vertical sectional view of my improved churn; Fig. 2 is a vertical sectional view thereof taken in a plane at right angles to that shown in Fig. 1; and Fig. 3 is a longitudinal sectional view of the dasher.

Referring more particularly to the drawing, the numeral 1 designates the churn body which is tapered from its lower end to its upper end, the side walls of the body being inclined their entire length.

The numeral 2 designates the cover of the churn, the cover being provided with a marginal flange 3 which is adapted to rest upon the upper edges of the body. Formed centrally in the cover is a slot 4 and formed on the upper face of the cover on opposite sides of the slot are upstanding bearing lugs 5 in which the ends of a shaft 6 are mounted.

Pivottally mounted intermediate of its ends on the shaft 6 is a dasher rod 7, the upper end of which provides a handle, and the lower end thereof being split to provide a pair of legs 8 between which a dasher 9 is secured.

The dasher 9 is formed from a plate of metal which projects beyond the opposite sides of the rod 7, and blades 10 are formed on opposite sides of the rod by punching portions of the plate outwardly, the blades being extended in a plane at right angles to the dasher and arranged parallel with the body of the dasher. The blades on each side of the rod are punched outwardly alternately in opposite directions, and the blades which are disposed in the same horizontal plane are extended in opposite directions, so that the blades on the opposite faces of the dasher are arranged in staggered relation. It will be noted that the inner ends of the blades bear against the dasher rods 7 which will prevent them from becoming easily distorted.

To provide means whereby water or other liquid contained within the churn body may be drawn therefrom, a vent 11 is formed in one wall of the body adjacent its lower end, the vent being normally closed by a plug 12. To detachably lock the cover to the body, a latch 13 is loosely connected at one end to the cover adjacent one edge thereof, the outer end of the latch being directed angularly and provided with an opening therein to receive a staple 14 or other suitable keeper therethrough, which is secured to one of the inclined side walls of the body.

One edge of the cover 2 is beveled as at 15 to substantially the same degree as the degree of inclination of the adjacent side wall, the wall being beveled from the lower face of the cover to the flange 3 formed thereon. By the provision of the beveled side wall 15 of the cover, it will be seen that when the cover 2 is in position and the latch 13 engaged with the keeper 14, accidental disengagement of the cover is prevented and tilting of the cover toward the side of the body in which the keeper is mounted is prevented by reason of the beveled wall of the cover engaging with the inclined side wall of the body. Tilting of the cover toward the front and rear walls of the body is prevented to any degree by the close proximity 110 of the side edges of the dasher to the front and rear walls of the body, but it will be

readily seen that when the latch 13 is disengaged from the keeper 14, the cover may be tilted toward the inclined side wall opposite from that in which the keeper is mounted, so that material may be poured into the churn body without the necessity of manually supporting the entire weight of the cover while the churn body is being filled, as the weight of the cover is supported 10 upon the upper edge of the inclined side wall of the churn body.

When it is desired to churn cream, the same is poured into the churn body in the above described manner, and the cover is 15 fastened in position by engaging the latch member 13 with the keeper 14, and the upper end of the dasher rod may be grasped and moved from side to side to oscillate the dasher within the churn. By the provision 20 of the plurality of openings in the dasher 9 formed by punching the blades 10 outwardly, the cream is quickly separated from the butter, and the cream may be easily drawn from the churn body by removing 25 the plug 12 from the vent 11, and it will be readily understood that after the cream has been drawn, the plug may be again inserted in the vent and a quantity of water poured into the churn body so that the butter may 30 be washed by oscillating the dasher, whereupon the water may be drawn through the vent upon removal of the plug, after which

the cleaned butter may be removed through the upper end of the churn after disengagement of the cover from the churn body. 35

Having thus fully described my invention, what I desire to claim and secure by Letters Patent is:—

A churn including a hollow body having a cover, a dasher rod pivotally connected intermediate of its ends to the cover and projecting therethrough, the lower end of said rod within the body being split to provide a pair of legs, a dasher plate secured to the legs and projecting beyond the opposite sides of the rod, said plate being provided in its projecting portions with punched-out blades arranged parallel with the body of the plate, the blades on each side of the rod being extended alternately in opposite directions, and the blades disposed in the same horizontal plane being extended in opposite directions, whereby the blades on the opposite faces of the dasher are arranged in staggered relation, the inner ends of said blades bearing against the sides of the dasher rod to prevent them from becoming easily distorted.

In testimony whereof I hereunto affix my signature in the presence of two witnesses. 60
JOSEPH HERMAN.
